HIGH SPEED PLANING MACHINE WITH
HYDRAULIC RAM DRIVEHeinrich Feilkas, Offenbach-on-the-Main,
GermanyApplication January 21, 1935, Serial No. 2,710
In Germany January 24, 1934

7 Claims. (Cl. 90—38)

This invention relates to a high speed planing machine with hydraulic ram drive by a pump with uniformly variable delivery quantity, which, controlled by a reversing element, acts on a piston arranged in a working cylinder and mounted on the end of a piston rod.

The known machines of this type are open to the objection that all the working speeds necessary for rough and smooth work cannot be governed by a single delivery pump of small dimensions, without special auxiliary arrangements.

The primary object of the invention is to overcome this objection. This is attained in that the reversing element cooperating with a reversing cock controls conduits delivering to both ends of the working cylinder so that merely by adjusting the reversing cock for roughing only the full piston side, for smoothing for the purpose of increasing the working speed both piston sides and for the accelerated return movement only the off-set side of the piston can be subjected to pressure, whereas, when the reversing element is in its intermediate position, the loading of the piston is interrupted.

In order to effect the return movement in any working position at the highest possible constant speed, the reversing element is connected with the delivery pump by clutch members which, when the reversing element is set for the return movement, adjust the pump for maximum raising.

By interposing an idle movement in the clutch members between the pump and the reversing element, provision is made for the shock-free reversal of the piston.

The displacement of the reversing element is effected by an auxiliary pump, the pressure oil of which can be employed for pressure lubrication after the reversal. The reversing element is also directly connected with a shaft effecting the travel of the table, this shaft, when disengaged, enabling a uniform driving of the table.

The planing machine consists substantially of a base plate serving as oil container, a ram shiftably mounted on a bed and driven by a power cylinder situated thereunder, a pressure oil pump with reversing valve and the necessary conduits, and a table with feed mechanism for carrying the work.

In the accompanying drawings those arrangements which are essential for the invention are illustrated, by way of example, partly diagrammatically.

Fig. 1 shows the hydraulic drive and the reversing device for the piston actuating the ram

and the drive for the table travel connected therewith.

Fig. 2 is a section on line II—II of Fig. 1.

Figs. 3 to 6 show the reversing valve in section on line III—III of Fig. 1, with the controlling member in different positions.

Fig. 7 shows in section and on a larger scale the ratchet clutch for intermittently feeding the work table.

Fig. 8 is a sectional view showing the other end 10 of the driving shaft of the ratchet clutch with the neighbouring bearing parts equipped with a claw clutch, the claw clutch being completely engaged for obtaining maximum table feed.

Fig. 9 shows the same arrangement as Fig. 8 15 with half engaged claw clutch for obtaining smallest table feed.

Fig. 10 shows the arrangement of recesses in one of the bearing parts serving for accommodating the clutch teeth, viewed in the direction of 20 the arrow I of Fig. 8.

Fig. 11 shows the arrangement of the teeth on the clutch part, viewed in the direction of the arrow II of Fig. 8.

Fig. 12 is a horizontal part section through the 25 control box taken at the height of the axis of the reversing cock.

The planing machine is driven for example by an electric motor 1 which drives a hydraulic pump 2 with oscillatable casing 3. When the 30 casing assumes the horizontal position shown in Fig. 1, the delivery is zero. By oscillating the casing 3 upwards into the position *a* indicated in dot-dash lines, the delivering quantity can be uniformly varied up to a maximum. The oil is 35 taken from an oil tank 4 through a suction pipe 5 supplied from the pressure side of the hydraulic pump through a pressure pipe 6 to a reversing element 7, from which it is fed through conduits 8 and 9 respectively to the power cylinder 10. In 40 this cylinder moves a piston 11 which on one side carries a piston rod 11' rigidly connected in the usual manner with the ram of the planing machine which is not shown on the drawings. During the outward movement of the ram the 45 full face 11a of the piston is operative, whereas during its return movement only the annular surface 11b is operative. The ratio between the two piston surfaces is about 2:1.

The reversing valve 13 consists of a housing 7 50 with a rotary valve 12 mounted therein, in the bore 13a of which valve a shaft 14 is axially shiftable. The bores and milled out portions necessary for conducting the pressure oil to the pressure conduits 8 and 9 are provided in the 55

housing 7 and in the valve 12. The pressure conduits 8 and 9 and a discharge conduit 15 extend in the section plane III—III up to the slide valve bore 13a. At this point the valve 13 has 5 two chambers 16 and 17 open towards the bore 13a. A shut off or reversing cock 18 is fitted in the pressure conduit 9 in the housing 7 transversely to the valve 12, said cock enabling the conduit 9 to be brought into communication 10 with a by-pass conduit 19 terminating in the slide valve bore 13a opposite the conduit 8. All channels communicating with the bore 13a are mutually displaced through an angle of 90°.

The pressure oil is supplied through a channel 15 20 extending from the pressure conduit 6 and leading to the chamber 16 in the valve 12. Diametrically opposite this channel 20 a by-pass 21 is arranged in the housing 7, which by-pass leads from the pressure chamber 16 to 25 the outer end of the housing. This by-pass 21 is closed by a portion of the reversing cock 18 which is not hollow, but is opened when the reversing cock is in a predetermined position by means of a bore 22 in this cock, so that the oil can flow off freely from the pressure chamber through 30 this by-pass into the collecting tank 4.

The rotary slide valve is adjusted by hydraulic means through the intermediary of a gear driven auxiliary pump 24 driven from the shaft 2a by 35 gear wheels 23, drawing oil out of the tank 4 through a suction pipe 25 and forcing it through a pressure pipe 26 into a chamber 27 arranged in a cover 28 placed on one side of the housing 7. This cover covers a semi-annular space 29 in the housing 7, half filled by a blade 30 fixed 40 on the rotary slide valve. Channels 31 and 32 extend from the chamber 27 to each end of the semi-annular space 29. A stepped piston valve 33 is mounted in the chamber 27 and adjusted 45 by adjustable abutments influenced by the piston 11 or the ram through the intermediary of transmission members not shown in the drawings. This stepped piston valve conducts, according to its position, the pressure oil to the one or the other side of the blade 30, so that the 50 rotary slide valve 12 is rotated through an angle of 90° in the one or other direction (Fig. 2). The stroke movement is limited by the blade striking against the housing.

55 The oil delivered by the auxiliary pump 24, does not return, after every rotation of the rotary slide valve, directly into the oil tank, but is forced into tubes 34, 35 serving for lubricating the whole machine, the tubes 35 being, during the reversing movement, alternatively connected with the portion of the semi-annular space 29 actually filled with oil.

The table travel is derived from the shaft 14 journalled in the rotary slide valve, said shaft 60 acting on the usual feeding mechanism of the table through the intermediary of a ratchet clutch 36 operating in one direction and of a bevel wheel gearing 37, 38. The ratchet clutch comprises a sleeve 36 slideable in the hollow hub 65 of the toothed wheel 37 and provided at one end with teeth 36' bevelled on one side which engage in the corresponding tooth gaps of a toothed ring 37' inserted and fixed in the hub bore owing to the fact that the sleeve 37 is pressed against 70 the ring 37' by the pressure of a spring 38''. In the sleeve 36 wedge grooves 41 are provided in which the wedges 42 fixed on the shaft 14 slide when this shaft is shifted. When the shaft 14 is driven in one direction, the teeth 36' cause 75 the toothed ring 37' to rotate, whereas they slide

the teeth of this ring compressing the spring 38'', when the shaft is driven in the opposite direction.

A claw clutch of special construction (see Figs. 8 to 11) is mounted on the end of the driving shaft 14, and serves for transmitting the swinging movements of the rotary valve 12 to the driving shaft 14. For this purpose a catch 49 is fixed on the shaft 14 axially shiftable in the rotary valve 12, which shaft carries on its periphery 10 four conically tapered projections 40. These projections engage in corresponding recesses 50 in the rotary valve 12. When the shaft is in the position shown in Fig. 8, the shaft is rotated during a swinging movement so that the maximum table feed is attained. By pulling the shaft back into the position shown in Fig. 9, there is idle movement between the projections 40 and the recesses 50 so that in this position for example the shaft 14 carries out only half the 20 swinging movement and consequently reduces the table feed by one half as compared with the position according to Fig. 8. The table feed can be regulated by different intermediate positions.

In order to obtain a uniform table movement, 25 it requires, for example for bringing it quickly into its initial position when setting up a fresh workpiece, a clutch member 39 is fitted on the shaft 14 and when the shaft 14 is shifted further to the left, this member is brought into engagement with the axle of one of the wheels of the pump 24 through the intermediary of a suitable gearing. Thus, the shaft 14 is uniformly driven when the clutch between it and the rotary valve 12 has been disengaged.

The shaft 14 is always shifted the desired distance in longitudinal direction by hand, through the intermediary of an adjusting lever 41.

A lever 43 is fixed on the end of the rotary slide valve 12 extending through the cover 28, 44 and connected to the housing 3 of the hydraulic gear by a wire rope 44. Consequently, if the rotary slide valve 12 is rotated in one direction, the lever 43 lifts the housing 3 and adjusts the main pump 2 to maximum delivery.

The housing 3 of the main pump can further be adjusted by a toe cam 45 to a certain delivering quantity determining the forward speed.

The arrangement above described is operated 5 and operates in the following manner:—

It is supposed that the main pump 2, 3 adjusted by the toe cam to a certain delivery to be conducted through the pipe 8 to the face 11a of the piston 11, produces the desired forward 5 speed for the ram.

(a) Rough planing

If the machine is to carry out rough planing, the controlling elements assume the positions 6 shown in Figs. 2 to 4, Figs. 2 and 3 particularly show the position of the controlling parts during the return movement of the piston 11. The chamber 16, into which the pressure oil is fed through the conduit 6 and channel 20, communicates with the conduit 9 through the by-pass conduit 19 and reversing cock 18, so that the pressure oil can act on the annular face 11b of the piston 11 and push the piston towards the left. When the rotary slide valve 12 is in this position, its lever 43 raises the housing 3 of the main pump and adjusts this pump for maximum delivery. The return movement of the piston is therefore considerably accelerated as compared with its forward movement, not only on ac-

count of the smaller operative piston face 11b, but also on account of the maximum delivery from the pump.

Shortly before the end of the return movement abutments of the piston slide valve 33 influenced by the ram are shifted out of the position indicated in Fig. 2 towards the left by a distance b . Thus, the pressure oil delivered by auxiliary pump 44 is then fed through the channel 32 in front of the blade 30 which is thus turned through an angle of 90° in clockwise direction. During the shifting of the blade 30 the oil in the space 29 is forced through the channel 36 into the lubricating conduit 35 which is now opened. After reversal the pressure oil can flow back to the auxiliary pump through the lubricating conduit 34.

By the rotation of the rotary slide valve 12 the lever 43 has likewise been lowered so that the housing 3 of the main pump again bears on the toe cam 45 and the main pump is adjusted to the forward speed.

As shown in Fig. 4 the pressure chamber 16, during the forward movement, communicates with the pressure conduit 8 through which the piston face 11a of the piston 11 is loaded, so that the forward movement of the cam is effected. The oil on the rear side of the piston can flow to the discharge pipe 15 through the conduit 9, reversing cock 18, by-pass conduit 19 and channel 17.

(b) *Smooth planing*

To enable the same equipment to be also employed for smoothing work requiring increased speed, it is only necessary to adjust the rotary slide valve so that, during the forward movement, both sides of the piston 11 are subjected to pressure. The control elements then assume the position shown in Fig. 6. By loading the piston on both sides the piston speed is doubled owing to the ratio of 2:1 between the piston sides.

In this instance the reversing cock is turned through an angle of 90° so that, whilst shutting off the by-pass conduit 19, the two pressure conduits 8 and 9 are connected with the pressure chamber 16. The oil behind the piston 11 is then, during the forward movement, pressed through the conduit 9 into the pressure chamber 16 and thence through the conduit 4 together with the oil delivered by the main pump through the conduit 8 in front of the piston 11. Thus, the quantity of oil acting on the front of the piston will be enlarged by the quantity displaced from behind the piston and the speed of the forward movement is correspondingly increased.

For the return movement the rotary slide valve 12 is turned into the position shown in Fig. 5, in which the pressure chamber 16 is connected with the conduit 9 by the reversing cock, whereas the oil in front of the piston 11 can flow off through the conduit 8, channel 17 and pipe 15. In this position the pump 3 is likewise set for maximum delivery.

(c) *Stopping position*

In order to stop the cam immediately in any position it is only necessary to bring into its middle position the hand lever 46 which actuates the reversing cock 18. Thus, the channel 21 hitherto shut off by the reversing cock and which connects the pressure chamber with the external space, is uncovered by the bore 22 in

the reversing cock, so that the oil delivered by the pump 3 flows back into the oil tank free from pressure.

From the above described operations it will be clear that the adjusting of the machine for roughing- and smoothing-work and for stopping can be effected by a lever 46. The duration of the return movement is reduced as far as possible by simultaneous adjusting of the pump 3 for maximum delivery and maintained constant at all speeds of forward movement.

In order to attain a gentle reversing movement of the piston 11 an idle movement is provided in the clutch members which connect the rotary slide valve 12 with the adjustable part of the delivery pump. This may be attained, for example, by making the angle of rotation of the rotary slide valve 12 and therefore of the lever 43 twice as large as the angle of rotation of the pump housing 3. Thus, the pump, when changing over from forward to reverse movement, is only raised after the rotary slide valve has already performed half of its movement, so that oil can already pass to the other side of the piston through the conduit 9 shortly before the reversal of the piston. Consequently, the acceleration takes place gently, that is any pressure impulses which might otherwise occur during the reversal of the whole quantity of oil are avoided.

On the other hand, during the reversing of the piston from reverse to forward movement, the delivery of the pump during the first half of the rotation of travel of the rotary slide valve is first reduced and only thereafter is the oil flow reversed. Consequently, the most favorable effect is attained with the very simple means.

(d) *Feed and quick travel*

The periodical travel of the table is effected, as already mentioned, by the control valve 12 in that by throwing over the lever 41 to the right (Fig. 1), the control valve is coupled with the shaft 14 journalled therein, so that this shaft actuates the feeding mechanism by means of a ratchet clutch 36 operating in one direction during the return movement of the piston. If the shaft 14 is then moved to the left by the lever 41, the wedge-shaped noses 40 on the catch 39 will be gradually pulled out of the corresponding wedge grooves of the rotary slide valve, so that, according to the distance the shaft is shifted, there will be more or less play between the noses and grooves which represents more or less great idle movement between the shaft and the rotary valve. Consequently the full rotary movement of the valve is no longer transmitted to the shaft 14 and consequently the table travels for a shorter distance. Thus, the table travel can be regulated within certain limits by the lever 41.

In order to reduce the idle running periods it must be possible to continuously move the table not only by hand but also mechanically. The continuous movement must, however, only take place after the disengagement of the intermittent movement. This is attained by entirely uncoupling the shaft 14 from the rotary slide valve 12 by shifting further to the left and by bringing the catch 39 into engagement with the continuously rotating shaft 42 driven by the motor. Consequently, the feed and quick travel is actuated always successively in the simplest manner by a single lever.

A particular advantage of the invention consists in that all adjustments, such as those of the speed for the roughing stroke, the smoothing

stroke, the feed from zero to maximum, and the feed and quick travel can be carried out whilst the machine is running. Moreover, it has been possible by the reversing valve which unites every-
5 thing, to reduce the number of operating levers to a minimum and to arrange these on a small area of the outer wall where they are easily accessible.

The invention is not restricted to high-speed 10 planing machines but it may also be applied to other machine-tools wherein the tool or the work carries out a reciprocating movement.

The pump with variable delivery may likewise be of any suitable construction.

15 I claim:—

1. High-speed planing machine with hydraulic ram drive, comprising in combination a working cylinder, a piston reciprocable in said cylinder, a piston rod on one side of said piston reducing 20 the operative surface on this side of the piston, a main pump with uniformly variable delivery, a pressure pipe leading from this pump, a control element at the other end of said delivery pipe, a control housing accommodating said control element, said control element rotatable in both directions in said housing, a second pump with constant speed of rotation, a blade servo-motor connected with said control element, a pivot control valve between said servo-motor and 25 said control element, said second pump in conjunction with said servo-motor adapted to alternately shift said control element into its two extreme positions through the intermediary of said pivot control valve, by-passes in said housing 30 leading to said control element, a hand operated reversing cock arranged in the control housing and adapted to control said by-passes, a conduit leading from said control element to one end of said working cylinder, and a conduit leading from 35 said reversing cock to the other end of said working cylinder, said control element and said reversing cock being mutually adjustable to control said by-passes and conduits and place the large surface of said piston under pressure during the outward movement, the small surface of the piston during the return movement and in the case of 40 high working speed, such as for smoothing, both surfaces of the pistons during the outward run and the small surface of the piston during the 45 return motion.

2. In a high-speed planing machine as claimed in claim 1 coupling members connecting the rotatable selector valve with the portion of the variable main pump adjusting the delivery of the pump, said coupling members adapted to set the 5 main pump for maximum delivery when said selector valve is set for reverse motion.

3. A high-speed planing machine as specified in claim 1, comprising abutments on the ram adapted to indirectly influence the control element, and clutch members between said element and the main pump adapted to adjust said pump for maximum delivery when said element is adjusted to return movement by said abutments, said clutch members having an idle movement to 15 prevent the production of shocks during the reversal.

4. In a high speed planing machine as specified in claim 1 an oscillatable main pump casing, a pull element attached at one end to said casing, 20 a lever fixed on the control element and attached to the other end of said pull element so that during the rotation of said pull element said casing is oscillated at an angle of rotation smaller than that of said pull element.

5. In a high speed planing machine as specified in claim 1 the control element having a central bore, a table feed driving shaft longitudinally shiftable in said bore, a part driven by the auxiliary pump, and clutch members between said part 30 and said shaft adapted to transmit the movement of said part to said shaft to effect the table feed.

6. In a high speed planing machine as specified in claim 1 the control element having a central bore, a table feed driving shaft longitudinally shiftable in said bore, a part driven by the auxiliary pump, and conical clutch members between said part and said shaft adapted to transmit the movement of said part to said shaft to effect the 35 table feed.

7. In a high speed planing machine as specified in claim 1 a table feeding mechanism connected to the control element, and a blade servo-motor connected with the auxiliary pump and adapted to adjust said control element to actuate said mechanism, and pressure lubricating conduits connected to said motor and adapted to lead off the oil from the auxiliary pump to lubricate the 40 machine.

HEINRICH FEILKAS. 51
